ROBERT G. BROWN, OF GEORGE SCHOOL, PENNSYLVANIA, ASSIGNOR TO JOHN E. STREITELMEIER, OF CINCINNATI, OHIO.

PHONOGRAPH BRAKE.

1,419,214.

Specification of Letters Patent. Patented June 13, 1922.

Original application filed January 18, 1915, Serial No. 2,834. Divided and this application filed September 15, 1916, Serial No. 120,305. Renewed November 26, 1920. Serial No. 426,604.

To all whom it may concern:

Be it known that I, ROBERT G. BROWN, a citizen of the United States, and residing at George School, in the county of Bucks and State of Pennsylvania, have invented a new and Improved Phonograph Brake, of which the following specification is a full disclosure.

This is a division of my copending application No. 2,834 filed January 18th, 1915, and this case covers more particularly the mechanism including especially the brake element and the means for automatically controlling and operating the same.

One object of this invention is to provide a mechanism adapted first to be set in operation and then after a predetermined time interval to in turn cause a brake element to function in stopping the turn-table of a phonograph.

The primary object is to provide a mechanism that will very effectively enable a given record to be automatically replayed as many times as desired and then to automatically stop the machine.

Another object is to provide a unitary self-contained mechanism which can easily be applied to a conventional type of phonograph and which will render the same automatic to the extent of enabling it to replay a record any predetermined number of times and then to automatically stop the operation of the machine.

An object of the herein illustrated specific embodiment of this invention is to provide a mechanism that will normally be entirely free from the turn-table, but which by an appropriate electrical or mechanical latch will be thrown into engagement with said turn-table so as to derive motion therefrom and to utilize this motion for resetting the tone arm and finally for automatically stopping the turn-table.

Another object is to provide a lever fulcrum at two or more points and constructed to swing about one fulcrum to render a brake mechanism operative, and having latch mechanism controlling the other fulcrum.

A further object of this invention is to provide an attachment embodying an electrical or mechanical trip effective at the conclusion of a record to throw certain operat-

ing mechanism into action preferably by turn-table power, to lift the stylus and replace it at the beginning of the record, and to combine with said mechanism an adjusting instrumentality capable of determining the number of such replaying operations and of causing a brake automatically to stop the phonograph.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Fig. 1 is a plan view diagrammatically illustrating a conventional sound-arm, record and turn-table with my invention as an attachment applied thereto. Fig. 2 is an enlarged plan of a mechanism embodying my improvement. Fig. 3 is a front elevation thereof. Fig. 4 is a left-end elevation with the casing in section. Fig. 5 is a plan, similar to Fig. 2, showing the transmission unit in its tripped motion-receiving position, and showing some of the parts broken away to more clearly show the details of the escapement device. Fig. 6 is a right-end elevation, with the casing in section. Fig. 7 is a front elevation, with the casing in section to more fully show the brake mechanism. Fig. 8 is a detailed elevation of the counting wheel showing its bevelled ratchet-releasing nose. Fig. 9 is a plan of the sound conveying arm and of a modified construction of stop mechanism therefor.

Continuing by way of a more detailed analysis, it may be noted that this invention comprehends a trip or contact system which may operate either electrically or mechani-

cally, but which preferably operates through a contact element secured directly to each record, thereby avoiding the necessity of adjusting the mechanism whenever the records 5 are changed.

Preferably, the lifting mechanism is normally disconnected from the source of power so as to avoid wear of constantly running wheels and, to that end, the attachment is 10 provided with a wheel which is normally out of action but which can be shifted to engage the periphery of the turn-table and act to transmit power to the mechanism during the working periods.

Referring to the drawings, 1 indicates an element which is driven ultimately by the conventional phonograph motor and in this embodiment it is convenient to utilize the turn-table itself as the source of motion 15 and throw a frictional clutch to connect and disconnect the stylus-lifting mechanism therewith. A great advantage of this lies in the facility with which this instrument can be attached by any ordinary user to any 20 conventional phonograph. Such phonograph will also conventionally embody a suitable tone-arm 4 adapted to swing about a vertical axis over the record 5 and carrying a sound-box 3 having the usual stylus 2; the 25 whole being so arranged that the stylus can remain in the groove or be uplifted therefrom, this being here accomplished by having the sound-box carrier or gooseneck pivoted to the tone-arm to swing about a 30 horizontal axis. This invention embodies means which will lift the sound-box carrier about its horizontal axis in combination with means for swinging the tone arm about its vertical axis back to the 35 initial or starting point.

This invention contemplates a general mechanism adapted to enter into combination with the above-named conventional elements to function as above stated, and specifically it embraces all or many co-ordinated sub-combinations including (A) a sound-box lifter, which at appropriate intervals lifts and lowers the stylus; (B) a tone-arm shifter which carries the stylus 45 from the end to the beginning of the record; (C) a motion transmission which furnishes the necessary gears and shifts resulting in an actuation of the lifter and shifter; (D) a power connector which is in the nature of 50 a clutch mechanism and which at appropriate intervals connects the transmission with the primary source of power, which may 55 preferably be the turn-table itself but which may be any motor driven element; (E) a trip system which is effective automatically 60 to throw the power connector into action at the appropriate station in the record; (F) a control lever which automatically effects a disconnection of the power connector 65 and normalizes the relation of the trip to

the mechanism; (G) an adjuster which pre-determines the number of times the mechanism operates to replay the record; and (H) a brake which is conveniently caused to operate to conclude the performance.

These will be described in order.

The sound-box lifter, as shown by Fig. 1, consists of a davit 11 which is formed of tubing bent L-shaped and having its lower end journalled in a bearing 9 formed by a boss projecting from the base-plate 15. This base-plate is mounted adjacent the base of the tone-arm 4 so that the horizontal upper end of the davit may extend towards the tone-arm and terminate over the same 70 in a relation which will presently be more fully explained. A tension element such as the cord 12 (containing leading in and out wires) is anchored to the extremity of the davit 11 and also to an appropriate part of the sound-box 3, such as the upper side 75 thereof, and the extremity of the davit 11 is sufficiently higher than the axis 4^a so that a pull on the cord 12 will lift the arm 4^a about its horizontal axis, thus elevating the stylus. 80 This davit has an arm 16 whereby it may be oscillated by the motion transmitting mechanism.

The tone arm shifter is for the purpose 85 of causing the tone-arm to swing back to its starting position and, to avoid scratching the record by the stylus, this movement should not begin until the stylus has been raised clear of the record. This invention 90 contemplates a means that will come effectively into action only after the stylus has been raised and in this particular embodiment great simplicity has been attained by 95 intimately incorporating this means with the stylus lifter, and this has been done by 100 a peculiar relation between the axes 11^b and 4^c of the davit and tone-arm, respectively, and the arc of swing of the point 11^a. That is 105 to say, in its normal or stylus lowering position, the davit 11 is in such a position that the straight line from the point 11^a to the point 12^a is in substantially "dead center" 110 relation with the axis 4^c, but when the davit 11 swings into the position shown by Fig. 1, this straight line becomes in offset relation 115 with the axis 4^c with the result that a pull on the cord 12 not only tends to lift the stylus but also imposes a turning movement 120 on the tone-arm and urges it gently yet sufficiently towards its initial position.

The motion transmission is the mechanism or train of elements that results in the actuation of the stylus-replacing means by power derived from some motor-driven part, such as the turn-table 1; and which 125 preferably embodies reduction gears so that the ultimate motion will be slow and deliberate and the stylus will be handled gently and without jerks and save the record from scratches. In this embodiment, this 130

transmission is in part stationary and in part is bodily shiftable for power-connecting purposes. The stationary part comprises a shaft 19 pivoted at its lower end 5 in the base of the main frame or casting 15 and at its upper end to the cover-plate 20 which is also fixed to said frame by means of the posts 21 and 22. The upper end of this shaft 19 is provided with an 10 eccentric pin 19^a which is connected with the end of the arm 16 by means of the link 17 whereby the davit 11 may be rocked slowly. This shaft 19 derives motion from the clutch element or wheel 29 through a 15 train of reduction gears 24, 25, 26 and 27, the shafts of which are all pivoted to the side plates 23 of a rocking-frame. Both gear sets 24—25 and 26—27 have a pronounced reduction effect with the consequence 20 that the crank-pin 19^a is but very slowly turned, although the friction wheel 29 may rotate several times during each revolution of the turn-table.

The power connector is an arrangement 25 in the nature of a clutch and it enables the turn-table to operate during the normal playing of a record without any concomitant operation of the return mechanism. Preferably this means is located so as to 30 disconnect as many parts as possible from the source of motion, to avoid needless wear or noise, and preferably the wheel 29 is therefore entirely withdrawn from the turn-table. This is conveniently done by pivoting 35 the plates 23 of the sub-frame to the shaft 19 so that the shaft 28 of the friction wheel will be carried by the remote free-swinging portion of the sub-frame.

The position of this sub-frame is in 40 turn determined by the following arrangement:—

The lever control for the swinging power connector functions first to unlatch and resiliently swing the sub-frame to bring the 45 friction wheel 29 into engagement with the periphery of the turn-table and to maintain this engagement until the tone-arm has been shifted to its initial point, and in the meanwhile to effect a relatching of the control lever, and then through the same lever to withdraw the friction wheel and permit the record to be played without interference. This triple action is very easily effected by the multiple fulcrum lever system 50 comprising a lever 31 which is permanently pivoted at 30 to the plate 23 of the swinging sub-frame and which, in the position of the parts shown by Fig. 2, can (when unlatched) be turned about the stationary fulcrum point 18^a formed by a flat edge of the cam plate 18. That is to say, the end of the lever 31 has entered a right angle notch 32 in the cam-plate 18 so that it may rest against the edge 18^a thereof 55 which constitutes a stationary fulcrum ena-

bling the lever 31 at the point 30 to pry the plate 23 around the axis 19. Normally, the lever is held against this movement by means of a pin 33 which engages with a notch 34 of a latch 35 pivoted at 36 to 70 a frame-element and spring pressed into position by the pull of the spring 38 on the end of the arm 37. The rotation of the cam 18 begins the moment the wheel 29 starts to actuate the davit 11 and this 75 rotation is anti-clockwise and immediately brings the raised portion 18^a against the edge of the lever 31 so as to force its end away from the shaft 19 and swing the lever about the pivot 30 (the sub-frame remaining still) until the latch pin 33 has passed the notch 34 in the latch 35. This condition remains unchanged while the periphery of the cam-plate 18 rides against the edge of the lever 31 and until the point 18^a 85 passes the end of the lever 31, whereupon the fulcrum provided by the cam 18 will have disappeared and immediately its place is taken by the pin 33 so that the spring now tends to turn the lever 31 around the 90 pin 33 as a fulcrum and this tends to throw the pivotal connection 30 in the opposite direction and, of course, withdraws the sub-frame and the friction wheel 29 so that all motion ceases in the entire attachment. The 95 sub-frame continues to withdraw until the end of the lever abuts the part 18^a again, when the position of Fig. 2 is attained. This action has resulted in an elevation of the stylus, a swinging of the 100 tone-arm, and a replacement of the stylus. Now, the stylus is in a position to replay the record and will continue to do so until a trip system comes into effect to release the latch 35 and cause the attachment to refunction in restoring the stylus to its initial 105 position.

The trip system contemplates a means for causing the latch 35 to swing aside and release the pin 33 and this movement of the 110 latch 35 may be effected either mechanically or electrically, the latter possessing the advantage of making it unnecessary to reset the trip adjustment when a new record disc is placed in the machine. In this embodiment, a thin brass washer 14 is affixed to each particular record at a proper point so that it will close the circuit between the two spring fingers 13 when the stylus 3 reaches the end of the sound groove. The current passes 115 through the conductor which leads upwardly as indicated by 12^a and is secured at 11^a to the hollow arm of the davit 11 and it passes down this davit through the hollow post 9 (Fig. 6) and thence through the opening 9^a 120 and the end 12^a is fast to the one binding post α of the electro-magnet 39. The other binding post β may, by means of the small wire w , be grounded to the arm 15 to complete the circuit. Thus, whenever the con- 125

tact 14 functions, the electro-magnets will retract the latch 35 and the resetting of the stylus will take place.

The adjuster operates to determine the number of times the record is to be replayed; this number ranging from one to eight, or more, according to the construction. So far as has been explained, the above described apparatus would perform repeatedly an indefinite number of times, but this invention proposes a very simple arrangement for limiting the operation of the instrument. That is to say, a brake is caused automatically to stop the turn-tables; preferably just after the stylus has been uplifted and the tone arm returned. This brake consists of a rod 40 journalled to slide in the posts 41 and 22 and normally urged in the direction of the turntable by the spring 46 so that, if otherwise free, it will advance to project its end 42 (carrying a friction surface) through the opening 21^a in a post 21 and directly against the periphery of the turn-table, thereby stopping it. This movement is restrained, however, by means of a controller 43 having a number of teeth 44 which can cooperate with the periphery 45^a of a spiral track 45. This frame 43 can be adjusted, with the brake rod 40 by grasping the nob 43^a and it is provided with a pointer 50 co-operating with indication marks 51. Now, during each single revolution of the track 45, the end 47 will receive and pass one tooth, and if there be three teeth to pass then the instrument will operate three times before the brake is released by the sharp nose 47 which rides under and lifts up the smooth portion 48. The releasing point depends upon the location of the end 47 of the track and this will preferably be such that the davit will be moved to its uplift position.

For the purpose of limiting the swing of the sound conveying arm, I provide a stop member 52 journalled on an upright stud 53, which also serves as a securing member for the shelf 20. This stop member has an L-shaped head 54, having a short and long arm, and may be turned on the upright to bring either into the path of movement of the sound conveying arm, alternately serving for relatively different standard sizes of records. While the stop is only adapted for use with records of two different diameters it may be interchanged with a stop member having stop arms of different lengths to accommodate records of any size.

In Fig. 9, I have shown a modified form of stop provided with a spring retaining clip engaging with a series of notches in the supporting upright. A rotation of the stop arm in a clockwise direction will engage the spring clip in either of the notches, while the shape of the clip and notches will prevent retrograde movement and form a rigid abutment.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus revealed this invention, I claim as new and desire to secure the following combinations of steps and elements, or equivalents thereof, by Letters Patent of the United States:—

1. A phonograph brake-device combining a turn-table and a stylus; a mechanism operating under the power of said turn-table for repeatedly lifting said stylus; a brake; and an adjustment operated by said mechanism for causing said brake to function after said stylus has been uplifted for the predetermined number of times.

2. A phonograph brake-apparatus combining a frame adapted to be mounted adjacent a conventional turn-table; a brake-element movably mounted on said frame to engage and arrest the turn-table; means also on said frame adapted to co-operate in lifting a conventional stylus; and mechanism adapted to derive motion from said turn-table for operating said means to gradually lift said stylus and subsequently control said brake-element.

3. A phonograph brake-apparatus combining a frame adapted to be mounted adjacent a conventional turn-table; a brake-element movably mounted on said frame to engage and arrest the turn-table; means also on said frame adapted to co-operate in lifting a conventional stylus; mechanism adapted to derive motion from said turn-table for mechanically operating said means and controlling said brake-element; and means for automatically interrupting the propelling relation between said turn-table and said mechanism.

4. A phonograph brake-apparatus combining a frame adapted to be mounted adjacent a conventional turn-table; a brake-element movably mounted on said frame to engage and arrest the turn-table; means also on said frame adapted to co-operate in lifting a conventional stylus; and mechanism adapted to derive motion from said turn-table for mechanically operating said means and controlling said brake-element, said mechanism being so related to the stylus lifting means as to operate it before releasing the brake-element.

5. A phonograph brake-apparatus combining a main frame; a sub-frame; a motion receiving wheel journalled in said sub-

- frame; a single-convolution worm deriving rotation from said wheel; mechanism actuated from said wheel for repeatedly shifting the position of said sub-frame; a brake element; and a toothed part normally engaging said worm to hold said brake inoperative and adapted to release the same when it overrides said worm.
6. A phonograph brake-apparatus combining a main frame; a sub-frame pivoted thereto; an element pivoted to said sub-frame; a cam shaped stop for limiting the movement of said element in one direction; a spring urging said element against said stop and thereby effective to advance said sub-frame; a latch adapted to engage said element to restrain the advance of said sub-frame; a wheel in said sub-frame adapted to turn said cam first to latch said element and then to employ it in withdrawing said sub-frame; a worm deriving rotation from said wheel; a toothed part engaging said worm; and a brake element controlled by said engagement.
- 25 7. A phonograph brake-apparatus combining a rotatable element adapted to be connected with a source of motion; a frame adapted to shift said element; a lever adapted to turn on either one of a plurality of centers; a spring enabling said lever when turning about one center to advance said frame; a latch adapted to form a fulcrum to enable said lever to turn about it as a center and retract said frame; means for swinging said lever about said fulcrum; and a brake mechanism controlled by said element.
8. A phonograph brake-apparatus combining a rotatable element adapted to be connected with a source of motion; a frame adapted to shift said element; a lever adapted to turn on either one of a plurality of centers; a connection enabling said lever when turning about one center to advance said frame; a latch adapted to form a fulcrum to enable said lever to turn about it as a center and retract said frame; means for swinging said lever about a third center to render said latch operative; and a brake mechanism controlled by said element.
- 10 9. A phonograph brake-apparatus combining a shiftable frame; a lever pivoted thereto; a latch; means for swinging said lever about its pivot to engage said latch; means for moving said lever about the latch as a fulcrum to shift said frame; a transmission element adapted to be connected with a source of power by the shifting of said frame; and a brake controlled by said element.
- 15 10. In witness whereof, I hereunto subscribe my name, as attested by the two subscribing witnesses.
